TOY PISTOL

Filed Sept. 17, 1928

INVENTOR.

Thomas E. Webb.

BY

James G. Webb,

ATTORNEY.

UNITED STATES PATENT OFFICE

THOMAS E. WEBB, OF SAN FRANCISCO, CALIFORNIA, ASSIGNOR OF ONE-HALF TO JOHN R. HILLER, OF SAN FRANCISCO, CALIFORNIA

TOY PISTOL

Application filed September 17, 1928. Serial No. 306,372.

The present invention relates to improvements in toys generally and more particularly to those of a catapultic character constructed in semblance of firearms, such as 5 guns and pistols, and provided with an "ammunition" possessing in combination the properties of both "projectile" and "propellant", after the manner of an elastic member.

10 As herein illustrated, the device comprises a member of pistol-like form having a "trigger" mechanism adapted for the retention of one end of an elastic member, the body of this member being stretched forwardly with its 15 other extremity in retained relation with the muzzle of the pistol-like body.

The primary object of my invention is the provision of a toy of gun or pistol-like appearance, the "ammunition" of which is of 20 combination projectile and propellant character and constituted of a single elastic element.

A further object of the invention is to provision of a toy of the class designated embodying an elastic member constituting both projectile and propellant, together with novel means for gripping and retaining this member in "loaded" relation with the toy body preliminary to its "firing".

30 An additional object of the invention is to provide a toy of the class designated that is of extremely simple form, cheap construction and durable character.

Other objects and advantages of the invention will become obvious to those skilled in the art, as this specification progresses and be more fully set forth in the claims hereto appended.

In the accompanying drawings, forming a 40 part of this specification, and in which similar characters of reference refer to like parts, throughout:

Figure 1 is a side elevation illustrative of the preferred form of my invention, in which 45 the combined projectile and propellant is shown in the form of an elastic band positioned in readiness for "firing", the dot-and-dash line A indicating the position of the band immediately following the release of its "trigger"-retained extremity, and

B that of its complete release from the device and direction of travel in flight toward its target;

Figure 2 is a top plan view of the device as shown in Figure 1, and is further illustrative of the shape of the barrel, the elastic band retaining within itself the properties of both projectile and propellant, and the "trigger mechanism"; and

Figure 3 is a mutilated view illustrative of 60 a slightly modified form of the propellant-projectile, comprising, in this instance, a single strip of elastic material instead of one of a looped or band character.

Referring more particularly to the drawings, the body of my improved toy-gun, or pistol is, preferably, stamped or cut from wood to form a butt, or grip, 5, a "magazine" section 6, and a barrel section 7. If desired, 70 the configuration thus secured may be employed as a pattern and the toy cast in light metal.

The grip section 5 is angularly slotted, as indicated at 8, and, as here shown, serves to form a seat for the "trigger" mechanism, which, in this instance, embodies a member 9 of spring clothespin-like construction, comprising the matched sections 10 and 11 with recessed or notched upper ends 12, and a spring member 13 normally holding the recessed ends of the sections 10 and 11 in tightly closed relation.

The section 10 of the "trigger" mechanism is securely pinned in the slot 8 by means of pins 14 extending through the side walls 15 and 16 of the grip section 5, with the upper end of the member 9 projecting slightly above the upper "sight" edge 17 of the "gun-barrel", as shown in Figure 1, and the lower end 18 of the section 11 extending slightly beyond the curved outer surface 19 of the grip section and forming the "trigger" proper.

The combination projectile - propellant 95 preferably comprises a looped elastic band 20, as shown in Figures 1 and 2, or it may comprise a single flat elastic member, as represented in the modified form in Figure 3, or, if desired, either of these may be of cord-like character.

In "charging" the toy-gun, the looped end 22 of the band 20 is first fitted over the muzzle 23 of the barrel 7 and its opposite end 24 stretched rearwardly to and inserted between the recessed portions 12 constituting the jaws of the member 9, the "trigger" member 18 being, the while, depressed by hand compression to hold the jaws apart to permit of this insertion and immediately thereafter released to permit their securely gripping and holding the end 24 until its release is desired, which is accomplished by the depression again of the member 18. A reversal of the process of securing the band 20 in extended position between "trigger" mechanism and muzzle may be employed with equal facility, if so desired.

In the modified form shown in Figure 3, the elastic member 21 is provided at its forward end with an eyelet 25, adapted for engagement with a pin 26 borne by the muzzle, and at its opposite end with a thickened portion 27 serving to facilitate its being gripped by the "trigger" member 9 and to add weight to its head for stabilization in flight.

Assuming that the toy has been "charged", as provided for and shown in Figures 1 and 2, and is in readiness for "firing", the toy-gun is levelled at the target, the "trigger" member 18 depressed by gripping pressure upon the butt 15 releasing the end 24 of the "charge" or band 20, which hurtles upwardly and forwardly, as indicated at A, to finally assume the straightened-out position for flight indicated by B, with a complete reversal of band ends and an aligned course with the barrel toward the object aimed at.

Having thus described my invention, I claim, and desire to secure by Letters Patent:

40 1. An article of the class described, comprising a member of pistol-like form embodying a butt-end and a muzzle, an angular slot formed in the butt-end thereof, a "trigger" mechanism mounted in said slot comprising a spring-controlled gripping member having gripping jaws and a "trigger" section, and means constituting both a projectile and a propellant adapted for stretching between said muzzle and said "trigger" mechanism.

45 2. An article of the class described, comprising means, including a "trigger" mechanism and a muzzle, said "trigger" mechanism embodying spring pressed gripping jaws, an elastic member, constituting both projectile and propellant, stretched between said gripping jaws and muzzle, and means whereby the application of gripping pressure to said "trigger" mechanism serves to cause 50 the release of the gripped end of said elastic member and permit, through its retraction, its projection from said muzzle in aligned course therewith.

55 3. In an article of the class described, means constituting a gun-butt and barrel,

a "trigger" mechanism therefor comprising a member embodying spring pressed gripping jaws having correspondingly notched upper ends and adapted for angular disposition in the butt thereof, and an elastic band stretched between the muzzle of the barrel and the "trigger" mechanism, one extremity of said band being retained by said muzzle and the other extremity gripped by said notched jaws, the ejection of said band from said stretched position being dependent upon its elasticity and its release from said gripping jaws through gripping pressure applied to said "trigger" mechanism.

60 4. A toy of the class described, comprising a member embracing the general contour of a pistol and including a butt and a barrel, an angularly disposed slot formed in said butt, a "trigger" mechanism mounted in said slot and comprising a pair of spring pressed gripping members, one of which is rigidly secured in said slot and the other free for gripping and releasing action relative thereto, and an elastic band combining, through its elasticity, the properties of both projectile and propellant and adapted to be stretched between the muzzle end of the barrel and the "trigger" mechanism, with its free end securely gripped between said gripping members for subsequent release therefrom through pressure applied to said gripping member.

In testimony whereof I hereunto affix my signature.

THOMAS E. WEBB.
